UNITED STATES PATENT OFFICE

HENRY LANGE, OF QUINCY, ILLINOIS, ASSIGNOR TO QUINCY STOVE MANUFACTURING CO., OF QUINCY, ILLINOIS

DESIGN FOR A RANGE

Application filed September 22, 1932. Serial No. 45,015. Term of patent 14 years.

To all whom it may concern:

Be it known that I, HENRY LANGE, a citizen of the United States, and a resident of the city of Quincy, county of Adams, and State of Illinois, have invented a new, original, and ornamental Design for a Range, of which the following is the specification, reference being had to the accompanying drawing, forming a part thereof.

The figure is a perspective of the range of my invention, illustrating the essential features of its design wherein there is provided and illustrated a novel single dial control for the gas burners and an oven control.

I claim:

The ornamental design for a range as shown and described.

HENRY LANGE. [L.S.]
